FUEL CONTROL SYSTEM

William A. Ray, North Hollywood, Calif., assignor, by
mesa assignments, to International Telephone and
Telegraph Corporation, New York, N.Y., a corporation
of Maryland

Filed Apr. 11, 1963, Ser. No. 272,406
2 Claims. (Cl. 158—125)

The present invention relates to fuel control systems for controlling the safe burning of gas at a main burner.

Briefly, the system described herein involves a main gas burner, a pilot burner for igniting gas from the main burner, control apparatus functioning to operate to supply gas to the main burner only when there is a pilot flame at the pilot burner. The pilot flame is established by electric ignition.

One feature of the system is that closure of a switch results in an automatic interlocked sequence of events wherein the pilot flame is first established by electric ignition, after which, with some time delay, the previously mentioned control apparatus functions automatically to allow gas flow to the main burner.

In one form of the invention the control apparatus involves a thermocouple heated by the pilot flame and in a second form of the invention the control means involves the heating of a mercury-filled bulb. In both forms of the invention, gas flow to the main burner is through two series-connected valves, the first or upstream valve being electrically operated substantially simultaneously with the electrical igniting means for supplying gas to the pilot burner, while the second or downstream valve is opened automatically only when a safe pilot flame has been established and only after some time delay during which the thermocouple or mercury bulb, as the case may be, is heated sufficiently to cause operation of such second or downstream valve.

It is therefore a general object of the present invention to provide a fuel system of the character described.

A specific object of the present invention is to provide a fuel system of this character wherein, in the shutdown condition of the system, gas is prevented from flowing both to the pilot and main burners.

Another specific object of the present invention is to provide a system of this character in which operation of a switch results automatically in establishment of a pilot flame followed, with some time delay, by establishment of the main burner flame.

Another specific object of the present invention is to provide a system of this character which incorporates a thermocouple heated by a pilot flame.

Another specific object of the present invention is to provide a system of this character incorporating a mercury bulb heated by the pilot flame.

Another object of the present invention is to provide a system of this character in which there is proper interlocking to assure the above-indicated safe sequence of events.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

FIGURE 1 illustrates a system embodying features of the present invention using a mercury bulb.

FIGURE 2 illustrates a system embodying features of the present invention using a thermocouple.

Referring to FIGURE 1, the same includes a main burner 10, a pilot burner 12 mounted in close proximity to the main burner for igniting gas flowing from the

2

main burner, a spark igniter 14 mounted in close proximity to the pilot burner 12 for igniting gas flowing therefrom to establish the pilot flame, a mercury-filled capillary bulb 16 mounted in close proximity to the pilot burner 12 so as to be heated thereby for performing a control operation as described later.

The main burner 10 is in communication with the outlet opening 18 of valve casing 20 via main burner line 22. Gas is supplied to such casing 20 through its inlet opening 24 and gas can flow to the main burner 10 only when the two series-connected valves 26 and 28 are open, the valve 26 being referred to as the first or upstream valve and being electrically operated and the valve 28 being referred to as the second or downstream valve and being operated in accordance with the heated condition of the mercury bulb 16.

The pilot burner 12 is connected via the pilot burner line 30 to an opening 32 in casing 20 at a location between valves 26 and 28 such that gas may flow to the pilot burner 12 when the electrically operated valve 26 is open and regardless of the open or closed position of the downstream valve 28.

The valves 26 and 28 are normally closed, the valve 26 being closed by coil compression spring 34 which acts between the valve closure member 36 on diaphragm 38 and a stationary portion of the magnetic coil and core structure 40 that includes coil 42 to thereby normally press the movable closure member 36 against the annular valve seat 44.

The valve 28 is normally closed (unheated condition of the mercury bulb 16) by coil compression spring 46 acting between a closure member 48 for casing 20 and an intermediate portion of lever 50 which has one of its ends fulcrumed on a stationary support member 52 and which has its other end mounting a valve closure member 54 seatable on the annular valve seat 56. A supplementary biasing spring 58, weaker than spring 46, may be interposed between the closure member 54 and the casing 20 for assuring proper operation of the valve 28, it being noted that the closure member 54 is loosely mounted on lever 50.

The igniter 14, in the nature of a spark plug, is connected to the secondary winding 60 of ignition transformer 62 via a high tension shielded cable 64 which has its outer metal sheath grounded and its inner conductor connected in series with a stabilizing resistance 66, the resistance 66 being shielded also by the outer metal sheath. The transformer is so designed that without a load on the secondary, through energization of the igniter 14, insufficient current will flow through the primary circuit to maintain the solenoid valve 40 in open position.

The primary winding 68, comprising two series-connected sections 68A and 68B, is connected in series with a capacitor 70, a voltage source 72, a switch 74 and the operating coil 42 for valve 26.

In the following description of the operation of the system shown in FIGURE 1, it is assumed that initially the switch 74 is open and the mercury bulb 16 is in an unheated condition, in which case both valves 26 and 28 are closed. The system is placed in operation by closing switch 74 and such closure results substantially simultaneously in establishment of a spark at igniter 14 and the flow of pilot gas to the pilot burner 12 which is ignited by the spark to establish the pilot flame. The pilot flame heats the mercury bulb 16 to accomplish an expansion of the mercury in the capillary tubing 17 and this expanding force of the mercury is transmitted to the lever 50 which then moves in a clockwise direction in FIGURE 1 against the action of its biasing spring 46 to open the valve 28 and allow gas to flow to the main burner 10 where it is ignited by the pilot flame.

The system shown in FIGURE 2 includes parts which are identical with those in FIGURE 1 and for that reason such parts have identical reference numerals in both FIGURES 1 and 2. Essential differences between FIGURES 1 and 2 involve the use of a thermocouple 116 instead of the mercury bulb 16 and a pressure-responsive valve 128 in FIGURE 2 is used instead of the mercury-operated valve 28 in FIGURE 1.

The thermocouple 116 is connected to a coil 200 wound on a generally U-shaped core member 202 and serves to control a three-way valve 204 having ports 206 and 208, these ports 206 and 208 being closable by a flapper element 210 which serves not only as a valve element but also as an armature attractable by the core member 202. For this purpose the armature element 210 is pivoted on one end of the U-shaped core member 202 and is normally urged into closed position against the port 208 by the coil compression spring 212.

The valve 128 comprises a closure member 214 mounted on a diaphragm 216, the closure 214 being seatable on the annular valve seat 216A. It will be seen that the diaphragm 216 defines walls of two different gas chambers, namely a first upper gas chamber 220, which is in communication with the valve seat 44, and a second lower sealed chamber 222 within which the three-way valve 204 is mounted.

The chamber 220 is constantly in communication with the pilot burner line 30 through a path which includes: a passageway 224, channel 226 within which a pilot adjustment valve 228 is located, and the outlet connection 230, such passageway, channel and connection being formed in the wall of casing 20. Thus, when valve 26 is open, gas flows to the pilot burner 12 regardless of the condition of valve 128.

Chamber 220 is also in communication with the pilot port 206 through a passageway 232 in the valve casing. The other valve port 208 is in communication with the previously mentioned pilot outlet connection 230 through a passageway 234 in the wall casing.

The following described operation of the system shown in FIGURE 2 assumes initially that the switch 74 is open and the thermocouple 116 is in an unheated condition, and in such case both valves 26 and 128 are closed and port 208 is closed by the spring-pressed armature flapper 210. Also, under this condition, chambers 220 and 222 are in communication with each other through the open port 206 so that the pressure on opposite sides of the diaphragm 216 are balanced, thus assuring a closed condition of the valve 128, such closure being further assured by the coil compression spring 240 acting between the diaphragm 216 and a stationary part of the pilot valve 204.

The system of FIGURE 2 is started in operation by closing switch 74, such closure resulting in energization of the coil 42 and opening of valve 26 and also the development of an ignition spark at the spark igniter 14. This opening of valve 26 results in flow of pilot gas from chamber 220 and passageway 224 and pilot connection 230 to the pilot burner where such gas is ignited by the ignition spark. At this particular time the valve 128 remains closed, since the pressure acting on the topside of diaphragm 216 is equal to the pressure acting on the underside of diaphragm 216, the pressure to the underside being communicated through passageway 232 and port 206. The pilot flame then heats the thermocouple 116 which develops sufficient current, after a time delay required to heat the thermocouple, to cause the armature 210 to be moved to its other position wherein the port 206 is now closed and the port 208 is now open. This opening of

port 208 results in venting of the previously applied gas pressure in chamber 222 to the pilot line 30 via passageway 234 and connection 230 so that gas then escaping from chamber 222 is burned at the pilot burner. This reduction in pressure in the chamber 222 results in unbalanced forces on the diaphragm 216 with the result that the pressure in the upper chamber 220 is effective to move the diaphragm 216 and the closure member 214 thereon downwardly to open the valve 128 and allow the flow of gas to the main burner where it is ignited by the pilot flame.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

1. In a fluid control system; a valve structure having a first valve means interconnected with a pilot burner and having a serially related second valve means interconnected with a main burner positioned adjacent said pilot burner; a first actuator system for selectively operating the said first valve means and a second actuator system for operating the said second valve means responsive to the said operation of the said first valve means; the said first actuator system comprising fuel ignition means positioned adjacent the said pilot burner, electromagnetic means associated with said first valve means, and switch-controlled circuitry including a power source for simultaneously operating said electromagnetic means and said gas ignition means in mutual dependence on each other; and means included in said switch controlled circuitry for insuring that a failure of said ignition means disables said electromagnetic means; the said second actuator system comprising thermo-responsive means positioned adjacent the said pilot burner and mechanical operator means positioned adjacent the said second valve means, with operation of said mechanical operator means being controlled solely by said thermo-responsive means independent of said power source; and the said operation of said first valve means by the said switch-controlled circuitry permitting the passage of fuel from an inlet on said valve structure through said first valve means to said pilot burner where it is ignited by said fuel ignition system and energizes said thermo-responsive device to operate said mechanical means permitting the passage of fuel from said inlet through said first and second serially related valve means to said main burner where it is ignited by said ignited pilot burner fuel.

2. A fluid control system as set forth in claim 1 wherein said power supply comprises an alternating current source for generating a continuous open-gap arcing of said fuel ignition means and wherein said thermo-responsive means includes an expansible fluid reacting with flexible diaphragm positioned in direct mechanical contact with the said mechanical means.
